Primary Examiner — Kelley A Donnelly

(57) **CLAIM**

The ornamental design for a collective glove display, as shown and described.

DESCRIPTION

FIG. 1 shows a front left side perspective view of the collective glove display showing his new design;

FIG. 2 is a front side view thereof showing gloves positioned on the design;

FIG. 3 is a front side view thereof without the gloves positioned on the design;

FIG. 4 is a back side view thereof;

FIG. 5 is a top view thereof;

FIG. 6 is a bottom view thereof;

FIG. 7 is a left side view thereof;

FIG. 8 is a right side view thereof; and,

FIG. 9 shows the front side view thereof without the gloves positioned on the design, as shown in FIG. 3 with the hands moved upward and rotated inward to illustrate the movement of the design.

Any broken lines in the figures illustrate portions of the ornamental design that form no part of the claimed design.

1 Claim, 9 Drawing Sheets
